UNITED STATES PATENT OFFICE.

OTTO A. STUDT, OF OROVILLE, CALIFORNIA.

AUTOMATIC FLANGE OILER.

Application filed August 8, 1924. Serial No. 730,880.

To all whom it may concern:

Be it known that I, OTTO A. STUDT, a citizen of the United States, residing at Oroville, county of Butte, State of California, have invented certain new and useful Improvements in Automatic Flange Oilers; and I do declare the following to be a full, clear, and exact description of the same, reference being had to the accompanying drawings, and to the characters of reference marked thereon, which form a part of this application.

This invention relates to improvements in devices for lubricating the flanges of locomotive wheels to lessen the wear between the flanges and rails, especially on curves.

Various devices for the purpose have been tried out, but as far as I am aware, they are all constructed so that the lubricant is fed continuously to the flanges, not only when the engine is in motion, but when the same is standing still. This not only entails a waste of oil, but what is more serious, frequently causes a loss of traction between the rails and wheels when such traction is most necessary, as when starting, due to an accumulation of the lubricant on the rails after flowing down the flanges. Oil is the most effective preventative of flange and rail wear, but owing to the above described detriment to its use with the lubricating devices at present available, water is very often being used in place of oil, which is not as efficient for the purpose.

The principal object of my invention therefore is to allow of the use of oil without the disadvantageous feature above named, by providing a lubricator or oil dispenser so constructed and connected to certain moving parts of the engine that only when the latter is running will any oil be caused to flow to the flanges, in which case the feeding of the oil will be positive and automatic.

While a few drops of oil may pass to the flanges after the engine stops, no more than said drops will thereafter be fed to the flanges no matter how long the engine remains at rest, and without any manual valve-closing on the part of the engineer being necessary.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims. 60

In the drawings similar characters of reference indicate corresponding parts in the several views:

Fig. 1 is a fragmentary side outline of parts of the running gear of a locomotive, 65 showing my improved lubricator mounted in connection therewith.

Fig. 2 is a transverse view of the lubricator assembly.

Fig. 3 is a side view of the lubricator, detached. 70

Fig. 4 is a similar view, with the cover plate removed and partly in section.

Fig. 5 is a vertical cross section of the device. 75

Fig. 6 is a detached view of the lubricant measuring and dispensing member, detached.

Referring now more particularly to the characters of reference on the drawings, the numeral 1 denotes the drive wheels of the engine, which in this case is equipped with the Walschaert type of valve gear. This gear includes a fixed link 2 reciprocated through a certain arc from an arm 3 fixed on the main crank pin 4 of that wheel to 80 which the main connecting rod 5 extends.

I employ this link, which is standard construction, as the means for operating my lubricator, as will be hereinafter seen. Any other suitable reciprocating member on the 90 engine can however be utilized as well as this link when necessary, since all engines are not equipped with the above named type of valve gearings.

My lubricating means comprises a pair of 95 separate units, one for each front drive wheel of the engine, positioned just ahead of the wheels and substantially in longitudinal alignment therewith. These units depend from and are supported by a transverse oil-supply tank 6 strapped onto the engine frames 7. To keep the oil in a readily flowing condition in winter, a steam pipe 8, from the exhaust of the air pump or other steam-driven accessory of the engine, 100 passes through the tank.

Each unit A comprises a body 9 having an intake member 10 at its upper end and a discharge member 11 at its lower end in transverse alignment with the intake. The 110 latter is adapted to be connected to the tank 6, the connection supporting the body, while

5 a pipe 12 of suitable character projects downwardly from the discharge member and engages the flange of the wheel, at its junction with the tread, a suitable distance above the center line of the wheel. Additional supporting means for the body is preferably provided in the shape of U bolts 13 passed about the tank 6 and secured to lugs 14 on the sides of the body.

10 The body is hollowed out from its outer face to receive a cup bushing 15 having a circular bore, the intake and discharge openings passing through this bushing.

15 A cover plate 16 is mounted on the body over the hollow area thereof, and makes an oil tight closure therewith. This plate has a bearing boss 17 for a shaft 18 which projects into the body-area centrally thereof and has fixed thereon a disc 19. This shaft 20 is disposed so as to be parallel to the wheel axles of the engine. Fixed on the outside of this disc is an oil measuring, dispensing and valve member, comprising a split spring ring 20. This ring has a width sufficient to have a snug running fit between the back of the bushing 15 and the inner face of the cover, while the outer face of the ring, tending to spring outwardly, always makes an oil tight fit with the bore of the bushing.

25 Provided in the outer face of the ring 20, in transverse alignment with the intake and discharge openings, is a plurality of evenly spaced grooves 21 of predetermined length, preferably cut tangent to the ring, and thus forming a number of independent pockets. It will therefore be seen that when any pocket lines up with the intake, it will fill with oil, which cannot escape until with the rotation of the shaft and ring, said pocket is disposed in an inverted position above the discharge opening, allowing the oil to pass down through the latter and into pipe 12.

30 To insure that the pocket will be emptied of its oil, I mount a spring pressed plunger 22 in the casing just ahead of the discharge opening with respect to the direction of rotation of the ring.

35 This plunger is radial relative to shaft 18, and its inner end is shaped to fit the cross sectional area of the grooves, which it enters as the grooves move therewith with the rotation of the ring. This arrangement, as will be evident, causes the oil from each groove in turn to be wiped therefrom and cause to drop down the discharge opening. This is of especial benefit in winter, when the oil is very sluggish and tends to stick in the relatively small pockets.

40 The shaft 8 projects outwardly to a point about in transverse alignment with the link 2, and has on such end a ratchet wheel 23.

45 Turnably mounted on the shaft is a lever or control arm 24 carrying a pawl 25 en-

gaging the ratchets and causing the ratchet wheel and shaft to be advanced only when the arm is moved in a certain direction. Reciprocation of the arm, to intermittently cause such advancement of the shaft is had by means of a rod 26 or the like connected to the arm and to the link 2 a certain distance beyond its center of rocking movement. The movement of the arm is such, in this case, that the shaft will be advanced a distance equal to the spacing between two adjacent ratchet teeth with every reciprocation of the link or for every revolution of the wheels. In other words, a full revolution of the shaft will be had for the same 50 number of wheel-revolutions as there are teeth in the ratchet wheel, in this case 18 or thereabouts.

55 There being four oil pockets in the ring 20, four deposits of oil will be passed to the wheel flanges with each revolution of the shaft. I have found this proportion of parts and relative speed of operation to give very good results on engines having drive wheels of five feet diameter or thereabouts. It will be evident however that should a greater or lesser flow of oil be desired, the pockets may be changed both as to size and number, and the rate of advancement of the shaft 18 may be altered to suit different conditions.

60 From the foregoing description it will be readily seen that I have produced such a device as substantially fulfills the objects of the invention as set forth herein.

65 While this specification sets forth in detail the present and preferred construction of the device, still in practice such deviations from such detail may be resorted to as do not form a departure from the spirit of 105 the invention, as defined by the appended claims.

Having thus described my invention what I claim as new and useful and desire to secure by Letters Patent is:

110 1. An automatic wheel-flange lubricator for engines comprising a hollow body having opposed lubricant intake and discharge openings, a rotary valve member turnably fitted in the body between the openings and having a pocket adapted to alternately align with the discharge or intake opening, and means for operating said valve from a moving part of the engine in a manner to cause the valve to have a period of dwell 115 when the pocket is aligned with the intake or discharge opening.

115 2. A gravity feed flange oiler for engines including a hollow body having opposed lubricant intake and discharge openings, a 120 valve member interposed between the openings to control the flow of lubricant from one to the other, means for operating said valve from a moving part of the engine, and means positively preventing a flow of oil 125

from the intake to the discharge opening when the engine is stopped and regardless of the position of the moving part relative to the valve at the time.

5 3. An automatic wheel-flange oiler for engines comprising a hollow body having opposed lubricant intake and discharge openings, a rotary valve member mounted with a close fit in the body and having a peripheral pocket adapted to alternately aline with the intake and discharge openings when said member is rotated, and means between said valve and a moving part of the engine for so rotating said valve.

15 4. An automatic wheel-flange oiler for engines comprising a hollow body having opposed lubricant intake and discharge openings, a rotary valve member mounted with a close fit in the body and having a peripheral pocket adapted to alternately aline with the intake and discharge openings when said member is rotated, a connection between said valve and a reciprocating part of the engine, and means included 20 with said connection whereby with the reciprocation of said part the valve will be intermittently rotated in a continuous direction.

30 5. An automatic flange oiler for engines comprising a lubricant supply member, a pipe leading to the flange, and an oil measuring member between said pipe and the supply and arranged to take a predetermined amount of oil from the supply and 35 deliver it to said pipe at recurring intervals and only when the engine is running.

40 6. An automatic wheel-flange oiler for engines comprising a hollow body having opposed lubricant intake and discharge openings, a rotary valve member mounted with a close fit in the body and having a peripheral pocket adapted to alternately aline with the intake and discharge opening when said member is rotated, and means for 45 rotating the valve member only when the engine is moving.

50 7. An automatic wheel-flange oiler for engines comprising a hollow body having opposed lubricant intake and discharge openings, a rotary valve member mounted with a close fit in the body and having a peripheral pocket adapted to alternately aline with the intake and discharge opening when said member is rotated, a shaft projecting from the valve member, a ratchet wheel fixed on the shaft, an arm turnably mounted on said shaft, a pawl on the arm engaging the ratchet wheel, and a connection between the arm and a reciprocating 55 part of the engine.

60 8. An automatic wheel-flange oiler for engines comprising a body having a circular bore and opposed lubricant intake and discharge openings leading to the bore, a

disc turnably mounted in the body, and a split-spring ring mounted on the disc to turn therewith, said ring making close contact with the interior walls of the body and having a peripheral pocket adapted to alternately aline with the intake and discharge 65 openings when the disc and ring are rotated.

9. An automatic wheel-flange oiler for engines comprising a body having a circular bore and opposed lubricant intake and discharge openings leading to the bore, a member turnably mounted in the body-bore, means for rotating said member only when the engine is moving, and means whereby with such rotation a predetermined quantity 70 of the lubricant will be intermittently 75 passed from the intake to the discharge opening.

10. An automatic wheel-flange oiler for engines comprising a hollow body having opposed lubricant intake and discharge 80 openings, a rotary valve member mounted with a close fit in the body and having a peripheral pocket adapted to alternately aline with the intake and discharge openings when said member is rotated, means for 85 rotating said member, and means whereby as the pocket alines with the discharge opening with such rotation, the lubricant in the pocket will be positively wiped therefrom and into the discharge opening.

95 11. An automatic wheel-flange oiler for engines comprising a hollow body having opposed lubricant intake and discharge openings, a rotary valve member mounted with a close fit in the body and having a peripheral pocket adapted to alternately aline with the intake and discharge openings when said member is rotated, means for rotating said member, and a plunger mounted in the body just ahead of the discharge 100 opening in the direction of rotation of the valve, said plunger being arranged to enter and fit the pocket as the valve rotates and the pocket alines with the discharge opening.

105 12. An automatic wheel-flange lubricator for engines comprising a hollow body having opposed lubricant intake and discharge openings, a rotary valve member turnably fitted in the body between the openings and having a plurality of separated peripheral pockets, one pocket being adapted to aline with the intake opening while another is alined with the discharge opening, and means for rotating the valve from a moving part of the engine in a manner to cause the valve to have a period of dwell when the pockets are in the above named positions, whereby to provide time for the pockets to fill and discharge respectively.

In testimony whereof I affix my signature.

OTTO A. STUDT.
